(57) **CLAIM**

The ornamental design for an upper torso belt, as shown and described.

DESCRIPTION

FIG. 1 is a front right perspective view of the upper torso belt in use;

FIG. 2 is a front isometric view of the upper torso belt with the strap coiled;

FIG. 3 is a front view of the upper torso belt with the belt coiled;

FIG. 4 is a rear view of the upper torso belt with the belt coiled;

FIG. 5 is a right side view of the upper torso belt with the belt coiled;

FIG. 6 is a left side view of the upper torso belt with the belt coiled;

FIG. 7 is a top view of the upper torso belt with the strap coiled;

FIG. 8 is a bottom view of the upper torso belt with the strap coiled;

FIG. 9 is a front perspective view of the inner side of the upper torso belt;

FIG. 10 is a planar view of the inner side of the upper torso belt;

FIG. 11 is planar view of the outer side of the upper torso belt;

FIG. 12 is an end view of the upper torso belt, as viewed from the left;

FIG. 13 is an end view of the upper torso belt, as viewed from the right;

FIG. 14 is top plan view of the upper torso belt; and,

FIG. 15 is a bottom plan view of the upper torso belt.

The dashed lines on the design in FIGS. 1-3, 5, 9-11 illustrate stitching that forms a part of the claim. The broken lines depicting a person in FIG. 1 illustrate environment and do not form a part of the design.

The stippling shown in FIGS. 1-6 and 11 is intended to indicate a loop surface of a hook and loop attachment on the outer surface of the Upper Torso Belt and is not surface ornamentation.

The thin lines shown in FIGS. 2-6, 9-10 are intended to show contour and are not surface ornamentation.

The wavy lines in FIGS. 2, 6-9, 11, and 13-15 are intended to indicate a hook surface of a hook-and-loop attachment.
